DESIGN FOR A BUCKET-EAR.

Design No. 13,385, dated October 31, 1882.

Fig. 1

Fig. 2

UNITED STATES PATENT OFFICE.

JOHN L. POPE, OF CLEVELAND, OHIO.

DESIGN FOR A BUCKET-EAR.

SPECIFICATION forming part of Design No. 13,385, dated October 31, 1882.

Application filed August 2, 1882. Term of patent 7 years.

To all whom it may concern:

Be it known that I, JOHN L. POPE, of Cleveland, in the county of Cuyahoga and State of Ohio, have invented and produced a new and original Design for Bucket-Ears, of which the following is a specification, reference being had to the accompanying engravings, forming part thereof.

My invention relates to a design for bucket-ears; and it consists in certain novel features of configuration and ornamentation, all of which will be hereinafter more particularly described and specifically claimed.

In the accompanying engravings are shown two views of a bucket-ear—sometimes called a “kettle-ear”—embodying my new design, Figure 1 being an outside view, and Fig. 2 an inside view.

Similar parts in the two views will be found designated by the same letters of reference.

At *a* is the usual eye or perforation to receive the end or hook of the bucket bail or handle, and at *b b* are the usual holes through which the rivets or other devices are passed for the securement of the ear-piece to the bucket, as well understood by those familiar with the construction of this article of manufacture.

I have improved the contour of a bucket-ear, as will be seen in the engravings, by notching

its body portion at the point *c*, and cutting off the lower corners at *e e*, thus giving to the article a more finished and handsome appearance. I have ornamented this body portion externally by surrounding each hole *b* with a raised annulus, *i*, and by extending the neck *h* down part way between these rings *i* in substantially the shape of a spear-head, all as plainly shown. The metal surrounding the eyes *a* is of a spherical form on each side.

What I claim as my invention, and desire to secure by design Letters Patent, is—

1. A bucket-ear having substantially the configuration and ornamentation shown and described.

2. The body portion of a bucket-ear having the top and bottom edges parallel, and provided with the central notch, *c*, and cut-aways *e e*, as shown.

3. A bucket-ear having its body portion ornamented substantially as shown and described.

In testimony whereof I have hereunto set my hand this 17th day of July, 1882.

JOHN L. POPE.

In presence of—

L. S. FISH,
FRANK N. WILCOX.
